United States Patent Office.

DAVID B. TIFFANY, OF XENIA, OHIO.

Letters Patent No. 65,965, dated June 18, 1867.

IMPROVEMENT IN TOOLS FOR JEWELLING WATCHES.

The Schedule referred to in these Letters Patent and making part of the same.

TO ALL WHOM IT MAY CONCERN:

Be it known that I, DAVID B. TIFFANY, of Xenia, in the State of Ohio, have invented certain new and useful Improvements in Jewelling-Tools; and I hereby declare that the following is a true, full, and exact description of the same, reference being had to the accompanying drawings, and to the letters of reference marked thereon.

Figure 1 in the annexed drawings, which make a part of this specification, represents a side view of my jeweller's tool.

Figure 2 represents a plan view of an arm attached to the tool or vise.

Figure 3 designates a plan view of a second arm fastened to the opposite side of the vise.

The letter A represents a small hand-vise. To one jaw of the vise A, which is flat at top, is secured the arm b, by a screw furnished with the nut g. The arm b being slotted, as seen in fig. 2, can be raised or lowered at pleasure. A cylindrical elbow, c, which forms a part of arm b, is formed at right angles with b and with the plane at the top of the jaw to which b is attached. The elbow c has a circular hole through it, which is intended to receive the tools used by the operator. d represents another slotted arm placed on the opposite jaw to b, and secured in position by the screw that holds the two jaws of the vise together. The arm d, it will be seen, is made adjustable by means of the slot above mentioned and use of the nut s. The upper end of arm d is perforated to receive the set-screw a. E designates a circular screw tap, serrated at its periphery, and placed between the vise and the arm d. The object of the tap h is to screw the jaws of the vise together. The letters m and n represent two prolongations of the jaws of the vise, their intention being to hold rings the more firmly when they are operated on.

The mode of operating my invention is as follows, viz: The watch-plate, or object to be jewelled, is first secured in the vise by means of the circular screw e, with the part to be jewelled above the face of the vise. Then adjust the arm d by means of the nut s, and bring the set-screw a against the plate that is to be worked on, so as to support it and keep it firmly in its place. Now place the cutting-shaft or guide through the perforation in e; adjust its point to the centre of the hole to be jewelled. Whilst the point of the shaft is thus against the plate, secure the arm b by means of nut g. Next withdraw the centre-shaft, and put in its place a shaft with a flat, sharp end, by revolving which the socket to receive the jewel is formed. The flat end shaft is now withdrawn, and a cutter with a V-shaped end inserted, by the revolving of which a "bezel" or flange is formed, and this flange, being pressed around the jewel, holds it firmly in position.

Having thus fully described my invention, what I claim, and desire to secure by Letters Patent, is—

1. An adjustable arm, through which the cutters work, secured to either side of the vise, substantially as and for the purposes set forth and described.
2. An adjustable arm, d, provided with a set-screw, a, and secured to the side of the vise opposite to the former, substantially as and for the purposes set forth.
3. The combination of the two adjustable arms with circular tap e and nut g, operating as and for the purposes specified.

DAVID B. TIFFANY.
